GIROLAMO CONCATO, OF BROOKLYN, NEW YORK.

SHOCK-ABSORBER.

1,218,171.

Specification of Letters Patent.

Patented Mar. 6, 1917.

Application filed May 31, 1916. Serial No. 100,760.

To all whom it may concern:

Be it known that I, GIROLAMO CONCATO, a subject of the King of Italy, residing at Brooklyn, in the county of Kings and State 5 of New York, have invented certain new and useful Improvements in Shock-Absorbers; and I do hereby declare the following to be a full, clear and exact description of the invention, such as will enable others skilled 10 in the art to which it appertains to make and use the same, reference being had to the accompanying drawings, and to characters of reference marked thereon, which form a part of this specification.

15 The present invention has reference, generally, to improvements in shock-absorbers for vehicles, and the invention relates, more particularly, to a novel and simple construction of shock-absorber for attachment to the 20 axles of a vehicle, the same being, furthermore, a further improvement in the construction of shock-absorbers of the general type shown and claimed in my application for Letters-Patent of the United States, filed 25 August 3rd, 1915, Serial No. 43,372/15.

The present invention has for its principal object to provide a more compact and a more efficient construction of shock-absorber of the type above mentioned; and said invention has for a further object to provide, in 30 connection with such a shock-absorber, means for checking the violent reactions of the ordinary vehicle springs with which said shock-absorber coöperates.

35 Other objects of the present invention, not at this time more particularly enumerated, will be clearly understood from the following detailed description of the present invention.

40 The invention consists, primarily, therefore in the novel construction of shock-absorber hereinafter more fully set forth; and, furthermore, this invention consists in the various arrangements and combinations of 45 the several devices and parts, as well as in the details of the construction of the same, all of which will be more fully described in detail in the following specification, and then finally embodied in the claims which 50 are appended to and which form an essential part of said specification.

The invention is clearly illustrated in the accompanying drawings, in which:—

55 Figure 1 is a detail side elevation of my novel construction of shock-absorber as associated operatively with the axle and chassis supporting springs of a vehicle, such as a motor-car.

Fig. 2 is a front elevation of my novel construction of shock-absorber. 60

Fig. 3 is a vertical cross section of the same, taken on line 3—3 in said Fig. 2; Fig. 4 is a vertical transverse section of the same, taken on line 4—4 in said Fig. 1.

Fig. 5 is a horizontal section of the same, 65 taken on line 5—5 in said Fig. 1, looking downward; Fig. 6 is another horizontal section of the same, taken on line 6—6 in said Fig. 1, looking downward; Fig. 7 is still another horizontal section of the same, taken 70 on line 7—7 in said Fig. 1, looking downward; and Fig. 8 is also a horizontal section of the same, taken on line 8—8 in said Fig. 1, also looking downward.

Similar characters of reference are employed in all of the above described views to indicate corresponding parts.

Referring now to the said drawings, the reference character 1 indicates an axle of a vehicle, and 2 indicates the usual steel leaf-springs upon which the body or chassis of the vehicle is supported.

My novel construction of the shock-absorber comprises a pair of side plates 3, which are laid so as to extend longitudinally 85 against the sides of the axle 1. The reference character 4 indicates hanger-irons, which are arranged in pairs spaced longitudinally from each other so as to extend over the ends of said side-plates 3, and thus 90 depend from opposite sides of said axle 1. Each hanger-iron 4 is provided at its upper end with a laterally extending hanger-lug 5 which extends over the upper surface of said axle 1 and in engagement therewith, 95 so that said hanger-irons may be positively suspended from and supported by the axle 1. Each hanger-iron 4 is further provided, in a location spaced beneath said hanger-lug 5, with a laterally extending holding-lug 6 which extends beneath the under surface of said axle 1 and in engagement therewith, so that said hanger-irons may be positively held against upward movement relative to said axle 1. Each hanger-iron 4 is further provided at its lower extremity with inwardly and laterally projecting carrying-lugs 7, so arranged that a base or bottom-plate 8 may be supported thereon, and secured thereto by means of screws 9, or any 100 other suitable fastening means, thus suspending from and beneath the axle 1, in sta-

105

110

tionary and horizontal position, said base or bottom-plate 8. The ends of said side-plate 3 extend between the said respective hanger-lug 5 and holding-lug 6 of each 5 hanger-iron 4, and rest against the inner side of the latter, being affixed thereto by means of fastening screws 10, or any other suitable fastening means, and thus said side-plates 3 serve to maintain said hanger-irons 10 spaced longitudinally from each other in proper positions.

Each pair of laterally opposite hanger-irons 4 are rigidly bound together, in the above described relation to said axle 1, by 15 means of bolts and nuts 11, which pass through said hanger-lugs 5, and by means of similar bolts and nuts 12, which pass through said holding-lugs 6.

Formed in connection with longitudinally 20 opposite side-faces of said hanger-irons 4 are guide-portions 13 which provide slide-ways for purposes subsequently to be disclosed.

Arranged to slide between longitudinally 25 opposite guide-portions 13 on each side of said axle 1 are vertically movable slide-plates 14. The inner faces 15 of said slide-plates 14 slide upon or against the outer faces of said side-plates 3. Said slide-plates 30 14 extend downwardly below the axle 1, and their lower ends are joined together by means of a foot-plate 16 which extends horizontally therebetween and which is preferably formed integrally with said slide-plates, 35 although if desired it may form a separate part otherwise secured in connection with said slide-plates.

Extending outwardly from the exterior face 17 of each of said slide-plates 14, and 40 preferably forming an integral part thereof, is a buffer-lug 18. Each buffer-lug is provided with a downwardly depending seating-stud 19 projecting from the under side thereof, and adapted to receive and 45 thus maintain seated against said buffer-lug the upper end of a buffer or shock-absorber spring 20. Said buffer or shock-absorber springs 20 are preferably of the spiral compression type, and their lower ends are supported or based upon said base or bottom 50 plate 8, which is also provided adjacent to its ends, and in alignment beneath said seating-studs 19, with upwardly extending seating-studs 21, which engage said lower ends 55 of said springs 20 and thus hold the same in properly seated relation upon said base or bottom-plate 8.

The reference character 22 indicates a 60 cradle-member adapted to be pivotally connected to said slide-plates 14, so as to be capable of a slight oscillation or swing in a direction parallel to the axis of the axle 1. Each slide-plate 14 is provided, adjacent to its upper end, with an outwardly projecting journal-stud 23, the outer end of which is

provided with screw-threads 24. Said cradle-member 22 is provided with downwardly extending side-arms 25 having suitably disposed openings 26 in which said journal-studs 23 are received. A nut 27 screws upon the threads 24 of each journal-stud 23. The ordinary or steel leaf-springs 2 of the vehicle are supported upon said cradle-member 22, and are suitably secured thereto by the usual anchor-yoke devices 28 and their tie-members 29 and nuts 30.

As will be understood from an inspection of the drawings there is no rigid connection between the axle 1 and the vehicle springs 2 supporting the body or chassis of the vehicle, and the weight of the vehicle is carried on the yieldable buffer or shock-absorber springs 20, consequently the axle 1 has what I term a "floating" relation to the chassis or body of the vehicle. It therefore 80 follows that as obstructions are met with by the wheels of the vehicle, or any unevenness of road surface, the consequent shock, jerk or pound of the axle 1 is not transmitted immediately and directly through the 90 more or less stiff vehicle springs 2 to the chassis or body, but the rise or vertical movement of the axle 1 lifts the hanger-irons 4 and base or bottom-plate 8 carrying the effects of the shock or sudden upward movement to the buffer or shock-absorber springs 20 which compress or yield to said sudden shock or movement and thus absorb the violence of the same and greatly diminish its force before transmission 100 through the slide-plates 14 to the cradle-member 22, springs 2 and thence to the chassis or body of the vehicle. It will thus be apparent that not only are heavy shocks 105 absorbed and diminished by my novel shock-absorber before their effect can be transmitted to the chassis or vehicle body, but by virtue of the "floating" relation of the axle to the chassis or vehicle body, all the minor vibrations usually consequent upon traction 110 are practically eliminated, thus rendering the vehicle comfortable and stable as to its riding qualities.

The reference character 31 indicates a reaction check-plate, from the under side of 115 which extends downwardly a stem or shank 32. Said foot-plate 16 is provided with a centrally disposed opening or hole 33 through which said stem or shank 32 extends, and in like manner said base or bottom-plate 8 is also provided with a similar centrally disposed opening or hole 34 through which the extremity of said stem or shank 32 extends so as to project beneath said base or bottom-plate 8. The extremity 125 of said stem or shank 32 is provided with screw threads 35 upon which screws an adjusting nut 36. A recoil spring 37 is arranged and seated between said foot-plate 16 and said check-plate 31, and the tension 130

of said recoil spring 37 is easily adjusted by screwing up the nut 36 against the bottom of said base or bottom-plate 8 to pull down the stem or shank 32 and the check-plate 31 to compress the spring 37 to the degree desired. It will of course be understood that the devices just described serve to check any violent reaction of the ordinary vehicle springs 2, since the force of such reactions are transmitted through the cradle-member 22 and slide-plates 14 to the foot-plate 16 with the tendency to jerk upward the latter parts. This reaction or upward jerk is thereupon transmitted to the recoil spring 37 and absorbed and greatly diminished or eased thereby, since the spring is backed against the relatively stationary check-plate 31 which is anchored to the base or bottom-plate 8 which in turn is rigidly related to the axle 1 by means of the hanger-irons 4, as above described, and consequently the pound of such violent reaction of the vehicle springs 2 is absorbed by the recoil spring 37 before it can be transmitted to said axle 1, as will be readily understood from an inspection of the accompanying drawings. This arrangement adds greatly to the efficiency of the absorber and constitutes a novel and important improvement over the construction of my earlier shock-absorber described in my earlier application above identified.

Another point of novelty and improvement over my earlier construction of shock-absorber consists in arranging the main shock-absorbing springs 20 upon each side of the axle 1, thus not only providing for a more compact and less clumsy device as a whole, but also providing a better balance between the moving and stationary parts of the absorber and a better distribution and absorption of the shocks or jars.

I am aware that some changes may be made in the various devices and parts of my present novel construction of shock-absorber, as well as in the combinations and arrangements of said devices and parts, without departing from the scope of my present invention. I therefore do not limit my invention to the exact arrangements and combinations of the various devices and parts, nor do I confine myself to the exact details of the construction of said parts, as described in the foregoing specification, nor as illustrated in the accompanying drawings.

I claim:-

1. A shock-absorber comprising a plurality of hanger-irons adapted to be rigidly connected with an axle so as to depend therefrom, a horizontal base-plate supported by the lower ends of said hanger-irons, guide-portions providing slideways in connection with said hanger-irons, a pair of slide-plates mounted between the guide-portions of longitudinally opposite hanger-irons so as to be

vertically movable upon opposite sides of said axle, a horizontal foot-plate rigidly interconnecting the lower ends of said slide-plates, horizontal buffer-lugs extending outwardly from each slide-plate, resilient buffer-members mounted between said buffer-lugs and said base-plate, and means for supporting the body of a vehicle in connection with the upper ends of said slide-plates.

2. A shock-absorber comprising a plurality of hanger-irons adapted to be rigidly connected with an axle so as to depend therefrom, a horizontal base-plate supported by the lower ends of said hanger-irons, guide-portions providing slideways in connection with said hanger-irons, a pair of slide-plates mounted between the guide-portions of longitudinally opposite hanger-irons so as to be vertically movable upon opposite sides of said axle, a horizontal foot-plate rigidly interconnecting the lower ends of said slide-plates, horizontal buffer-lugs extending outwardly from each slide-plate, resilient buffer-members mounted between said buffer-lugs and said base-plate, means for supporting the body of a vehicle in connection with the upper ends of said slide-plates, and a recoil buffer-means anchored to said base-plate and adapted to engage said foot-plate of the slide-plates to check sudden upward movements or recoils thereof.

3. A shock-absorber comprising a plurality of hanger-irons adapted to be rigidly connected with an axle so as to depend therefrom, a horizontal base-plate supported by the lower ends of said hanger-irons, guide-portions providing slideways in connection with said hanger-irons, a pair of slide-plates mounted between the guide-portions of longitudinally opposite hanger-irons so as to be vertically movable upon opposite sides of said axle, a horizontal foot-plate rigidly interconnecting the lower ends of said slide-plates, horizontal buffer-lugs extending outwardly from each slide-plate, resilient buffer-members mounted between said buffer-lugs and said base-plate, means for supporting the body of a vehicle in connection with the upper ends of said slide-plates, a check-plate located above said horizontal foot-plate, a stem connected with said check-plate and extending downwardly through said foot-plate and said base-plate, an adjusting nut co-operating with the end of said stem beneath said base-plate, and a resilient recoil spring mounted between said check-plate and said foot-plate for the purposes described.

4. A shock-absorber comprising a series of hanger-irons adapted to be rigidly connected with an axle so as to depend therefrom, a horizontal base-plate supported by the lower ends of said hanger-irons, guide-portions

- providing slideways in connection with said hanger-irons, a pair of slide-plates mounted between the guide-portions of longitudinally opposite hanger-irons so as to be vertically movable upon opposite sides of said axle, a horizontal foot-plate rigidly interconnecting the lower ends of said slide-plates, horizontal buffer-lugs extending outwardly from each slide-plate, absorber 5 springs mounted between each buffer-lug and said base-plate, means for retaining said absorber springs in position, and a cradle-member having side-arms pivotally connected with the upper ends of said slide-plates 10 above said buffer-lugs, said cradle-member being adapted to be connected with and support the ordinary springs of a vehicle body.
5. A shock absorber comprising a series of hanger-irons adapted to be rigidly connected with an axle so as to depend therefrom, a horizontal base-plate supported by the lower ends of said hanger-irons, guide-portions providing slideways in connection with said hanger-irons, a pair of slide-plates mounted between the guide-portions of longitudinally 15 opposite hanger-irons so as to be vertically movable upon opposite sides of said axle, a horizontal foot-plate rigidly interconnecting the lower ends of said slide-plates, horizontal buffer-lugs extending outwardly from each slide-plate, absorber springs mounted between each buffer-lug and said base-plate, means for retaining said absorber springs in position, a cradle-member having side-arms pivotally connected with the upper ends of 20 said slide-plates above said buffer-lugs, said cradle-member being adapted to be connected with and to support the ordinary springs of a vehicle body.
5. A shock absorber comprising a series of hanger-irons adapted to be rigidly connected with an axle so as to depend therefrom, a horizontal base-plate supported by the lower ends of said hanger-irons, guide-portions providing slideways in connection with said hanger-irons, a pair of slide-plates mounted between the guide-portions of longitudinally 25 opposite hanger-irons so as to be vertically movable upon opposite sides of said axle, a horizontal foot-plate rigidly interconnecting the lower ends of said slide-plates, horizontal buffer-lugs extending outwardly from each slide-plate, absorber springs mounted between each buffer-lug and said base-plate, means for retaining said absorber springs in position, a cradle-member having side-arms pivotally connected with the upper ends of 30 said slide-plates above said buffer-lugs, said cradle-member being adapted to be connected with and to support the ordinary springs of a vehicle body.
- 35
6. A shock-absorber comprising a series of hanger-irons adapted to be rigidly connected with an axle so as to depend therefrom, a horizontal base-plate supported by the lower ends of said hanger-irons, guide-portions providing slideways in connection with said hanger-irons, a pair of slide-plates mounted between the guide-portions of longitudinally 40 opposite hanger-irons so as to be vertically movable upon opposite sides of said axle, a horizontal foot-plate rigidly interconnecting the lower ends of said slide-plates, horizontal buffer-lugs extending outwardly from each slide-plate, absorber springs mounted between each buffer-lug and said base-plate, means for retaining said absorber springs in position, a cradle-member having side-arms pivotally connected with the upper ends of 45 said slide-plates above said buffer-lugs, said cradle-member being adapted to be connected with and to support the ordinary springs of a vehicle body, and a recoil buffer-means anchored to said base-plate and adapted to engage said foot-plate of the slide-plates to check sudden upward movements or recoils thereof.
6. A shock-absorber comprising a series of hanger-irons adapted to be rigidly connected with an axle so as to depend therefrom, a horizontal base-plate supported by the lower ends of said hanger-irons, guide-portions providing slideways in connection with said hanger-irons, a pair of slide-plates mounted between the guide-portions of longitudinally 50 opposite hanger-irons so as to be vertically movable upon opposite sides of said axle, a horizontal foot-plate rigidly interconnecting the lower ends of said slide-plates, horizontal buffer-lugs extending outwardly from each slide-plate, absorber springs mounted between each buffer-lug and said base-plate, means for retaining said absorber springs in position, a cradle-member having side-arms pivotally connected with the upper ends of 55 said slide-plates above said buffer-lugs, said cradle-member being adapted to be connected with and to support the ordinary springs of a vehicle body, a check-plate located above said horizontal foot-plate, a stem connected with said check-plate and extending downwardly through said foot-plate and said base-plate, an adjusting nut coöperating with the end of said stem beneath said base-plate, and a resilient recoil spring mounted 60 between said check-plate and said foot-plate for the purposes described.
- In testimony that I claim the invention set forth above I have hereunto set my hand this 25 day of May, 1916.

GIROLAMO CONCATO.
